CLOTHES HANGER

Leonard G. Kirkegaard, Los Angeles, Calif., assignor to Leonard Hanger Co., Hollywood, Calif., a corporation of California

Application July 6, 1939, Serial No. 282,988

4 Claims. (Cl. 223—95)

This invention relates to a trouser hanger and has for its principal object the provision of a neat and efficient device upon which a pair of cuffed trousers can be quickly and easily placed; which will hold the trousers secure against falling so that they may be hung from hooks or other suspension devices; and which will act to stretch the trousers to maintain them in a smooth pressed condition.

10 Other objects and advantages reside in the detail construction of the invention, which is designed for simplicity, economy, and efficiency. These will become more apparent from the following description.

15 In the following detailed description of the invention reference is had to the accompanying drawings which form a part hereof. Like numerals refer to like parts in all views of the drawings and throughout the description.

20 In the drawings:

Fig. 1 is a side elevation of one form of the invention partially broken away to show the inner construction.

Fig. 2 is a plan view thereof.

25 Fig. 3 is an end view illustrating, in broken line, the position of the trousers thereon.

Fig. 4 is a detail cross section, taken on the line 4—4, Fig. 1.

Fig. 5 is a side elevation, partially in section, of 30 a second form of the invention.

Fig. 6 illustrates a bracket which may be used with the second form.

Fig. 7 is a plan view of the second form with the trousers in place thereon.

35 The first form of the improved trouser hanger comprises two folded, sheet metal members 10 upturned at their outer extremities to form cuff clips 11 and at their inner extremities to form hinge ears 12. Due to the fact that the member 10 is folded back upon itself, there will be two cuff clips 11 and two spring ears 12 on each member separated by a slide channel.

A pin 14 is riveted or otherwise secured through each pair of ears 12 to hingedly support the extremities of an inverted U-shaped, wire spring 15, the action of which is to constantly urge the two members 10 apart. The two members 10 are held in alignment with each other by means of a guide rod 16 which slides in the channel between the two sides thereof. The rod has upturned extremities 17 which slide between the two walled sides of the members 10 to prevent rotation thereof.

It can be readily seen that the two members 18 can be forced together against the spring 15

and when released, the spring will snap them outward until stopped by the upturned extremities 17 of the rod 16. Each pair of ears 12 are pressed together to form a closed shoulder against which the extremities 17 contact. The 5 spring 15 is preferably formed with a loop 18 for receiving a suitable hanging hook 19.

In hanging a pair of trousers upon the device, the two members 10 are placed against the inner side of one of the trouser legs. They are then 10 drawn toward each other by squeezing the spring 15 in the hand. The two cuff clips 11 are then passed upwardly into the cuff on the trouser leg. The other trouser leg is then similarly placed on the remaining cuff clips and the spring is released. This allows the two pairs of cuff clips 11 to expand outwardly in the two cuffs on the trousers to stretch them along their press line and securely hold them to the hanger. The edges of the cuff clips are rounded outwardly, as 20 shown at 13, to position their outer edges on the exact center or fold line of the stretched trouser legs.

The trousers can be easily released by simply 25 grasping the spring 15 in the hand and squeezing it to release the cuff clips.

If desired, a coat hanger can be easily incorporated with the device, as shown in broken line at 20 in Fig. 1. The coat hanger need consist of only a single piece of bent wire, looped to engage the hook 19 and turned inwardly at its two extremities to slide into the channel in the open ends of the member 10, as illustrated.

The form of the invention shown in Figs. 5 and 6 embodies the same principle but is designed as a more permanent fixture. This form comprises a slide rod 21 on the outer extremity of which a piece of sheet metal is folded to form a pair of outer cuff clips 22. A second piece of sheet metal is similarly folded around the rod 21 to form a pair of inner cuff clips 23. The inner cuff clips 23 are slidable along the rod 21 and are constantly urged apart by means of an expansion spring 24.

An offset portion 25 terminating in an end 45 hook 28 is formed in the rod 21 which acts as a stop for the inner cuff clips 23 and also fits within the folded clips at their fully extended position to maintain them vertical. This offset and hook also serves to allow a plurality of the devices to be inserted in a bracket member 26 by means of which they may be supported from a door, wall or other supporting surface. The bracket member 26 is formed with a series of 50 openings 27 for receiving the hooked extremities 55

28 of the rods. A plurality of indentations 29 are also formed in the surface of the bracket member to engage the hooked extremities of the rods to maintain them in parallel relation on the bracket member. The bracket 26 may be provided with suitable attachment ears 30 by means of which it can be secured to a supporting surface.

5 The operation and use of the second form is similar to that of the first form. In Fig. 7, the 10 trousers are illustrated in place upon one of the hangers of the second form. It will be noted how the turned back edges of the cuff clips follow around the fold in the ends of the trouser legs.

15 While a specific form of the improvement has been described and illustrated herein, it is desired to be understood that the same may be varied, within the scope of the appended claims, without departing from the spirit of the invention.

20 Having thus described the invention, what is claimed and desired secured by Letters Patent is:

25 1. A trouser hanger comprising: a pair of sheet metal members folded back on themselves to form a channel; a rod extending from the channel of one member into the channel of the other member; spring means for constantly urging said members outwardly on said rod; a pair of separated upturned portions on each member for entering the cuffs of a pair of trousers at each 30 side of said hanger; and upturned extremities on said rod positioned to engage said members to limit their outward movement.

35 2. A trouser hanger comprising: a guide rod; a slidable member on each extremity of the guide rod; a pair of separated, upturned cuff clips formed on each of said slide members for entering the cuffs of a pair of trousers at each side of said hanger; spring means for urging said members outwardly on said rod; and an outwardly turned vertical edge on each of said cuff clips for following the contour of said cuffs.

40 3. A trouser hanger comprising: a pair of

open-topped channel members having upwardly extending side walls defining a slide channel; a straight guide rod extending from the slide channel of one member into the slide channel of the other member to maintain said members in alignment with each other; pivot means extending between the side walls of each member adjacent its inner extremity; an inverted U-shaped spring pivotally connected at its extremities to the pivot means in the respective members and acting to normally urge said members apart; and a trouser cuff-engaging clip extending upwardly from each side wall on the outer extremity of each member, the clips at each extremity being separated so that a trouser leg may be supported by its cuff 15 at each side of said guide rod.

4. A trouser hanger comprising: a pair of open-topped channel members having upwardly extending side walls defining a slide channel; a straight guide rod extending from the slide channel of one member into the slide channel of the other member to maintain said members in alignment with each other; pivot means extending between the side walls of each member adjacent its inner extremity; an inverted U-shaped spring 25 pivotally connected at its extremities to the pivot means in the respective members and acting to normally urge said members apart; and a trouser cuff-engaging clip extending upwardly from each side wall on the outer extremity of each member, 30 the clips at each extremity being separated so that a trouser leg may be supported by its cuff at each side of said guide rod; and an up-turned end on each extremity of said guide rod, said latter ends being positioned between the upwardly 35 extending side walls of each channel member to prevent relative rotation between said latter members and said guide rod, said side walls being contracted adjacent their inner extremities to prevent withdrawal of said upturned ends. 40

LEONARD G. KIRKEGAARD.
